CLAIM

The ornamental design for a bluetooth enabled clock radio, as shown and described.

DESCRIPTION

FIG. 1 is a front, right side perspective view of a blue tooth enabled clock radio showing my new design;

FIG. 2 is a front view thereof;

FIG. 3 is a right side view thereof, the opposite side view being a mirror image;

FIG. 4 is a rear view thereof;

FIG. 5 is a top view thereof; and,

FIG. 6 is a bottom view thereof.

The broken line showing of the clock radio is included for the purpose of illustrating environmental structure and forms no part of the claimed design.
